METHOD OF MAKING CONTAINER CLOSURES

Harry Sebell, Boston, Mass., assignor, by mesne assignments, to Crown Can Company, Philadelphia, Pa., a corporation of Pennsylvania

Application September 16, 1936, Serial No. 101,153

12 Claims. (Cl. 113—121)

The present invention relates to methods of manufacturing container closures, and the principal object of the invention is to provide a container and a closure therefor of relatively simple and inexpensive construction which will form a tight seal with the container and yet will permit a full pouring opening from the container when the closure is removed.

Another primary object of the invention is to provide a method of manufacturing container closures, including a method of applying and sealing such closures to a container.

Ancillary to the main objectives of the invention, it is my object to provide a closure of the plug type which is equipped with a sealing ring, which ring is expanded into intimate engagement with the container wall.

It is also an object of the present invention to provide a method whereby a preformed plug type closure may be initially sealed with the container wall in such manner that the closure may be removed and reapplied without diminishing the effectiveness of the seal.

Another object of the invention is to provide several forms of plug type closures which may be manufactured and applied to a contained in accordance with the methods of the present invention.

The containers of the present invention are adapted for use in the packaging of various articles and materials, either dry or liquid, and with or without vacuum. Among the dry articles which may be packaged in the containers of the present invention are cigarettes, candy, mints, and the like. However, the present invention will result in the greatest convenience when employed in the packaging of such liquids as paints, which are of considerable weight and necessitate a tight closure to prevent leakage from the containers.

Such liquids as paints have heretofore been packaged in containers such as metal cans which conventionally are made from a rectangular sheet of metal usually bent into cylindrical form, the edges of the sheet being connected by a conventional lock or lap type seam. In the use of paints and the like it is necessary to provide a closure which may be removed and the contents partially taken from the can with a brush, after which it may be desirable to reapply the closure with the expectancy of again removing the same when the remainder of the contents of the container is to be used. When a container such as a metal can with a longitudinal side seam is used in the packaging of paints, it has been found

to be extremely difficult to provide a removable closure which will form an effective seal at the side seam of the can; it being evident that the conventional lock or lap type seam will distort the cylindrical contour of the interior of the mouth of the can, making effective sealing difficult.

It has formerly been the practice in overcoming this difficulty to equip the open end of the container with a seamless neck ring, said ring being formed from a single blank of material and usually being secured to the open end of the container by a double lock seam. When such a seamless neck ring is used, a closure of the plug type may be positioned therein to form an effective seal, the plug closure engaging the interior of the seamless neck ring without contacting the end of the longitudinal side seam of the can.

While such containers have been successfully used, the cost of the container is materially increased by reason of the additional metal needed to form the seamless ring as well as the cost involved in forming and connecting the same with the container mouth.

To overcome the above mentioned difficulties without increasing the cost of manufacture, I have devised the container and methods of the present invention, which container employs a closure of the plug type having an annular groove in the outer wall of the skirt of the plug, which groove contains a sealing material of any appropriate composition adapted to intimately engage the wall of the container. The metal at the back of the above mentioned groove is upset after the closure is inserted in the container mouth, so that the sealing material will be firmly pressed against the container wall.

Plug closures of the above type have heretofore been ineffective due to the difficulty of applying the sealing material to the vertical skirt of the plug. Rings of rubber in solid condition applied to the groove of the skirt have not proved to be satisfactory, as they become unevenly worn and torn due to the movement of the ring within the groove when the closure is applied to and removed from the container during the normal use of the latter.

The sealing material which I have found to be most efficient is any one of the well known compounds applied in liquid form and permitted to solidify. A sealing compound when applied in this manner will effectively fill the groove in which it is disposed and having solidified therein will be adhesively bound to the wall of the

groove. The sealing compound may be of any appropriate composition, but a compound having a base of latex rubber has been found to be effective.

- 5 Heretofore, it has not been possible to apply a liquid sealing material to such closures as those of the plug type having a vertical wall or skirt with a groove therein for the sealing material because it was not possible to evenly distribute 10 the material in the groove, as the same would flow from the groove, before it solidified sufficiently to remain in position.

In order to overcome the above difficulties I have devised the closures and methods of the 15 present invention in which the sealing material is applied to the closure before the same is completely formed, and when the closure blank is in substantially flat condition. The sealing material is permitted to solidify while the blank is 20 in substantially flat condition, after which the blank is finally formed for application to the container.

The drawings, which are illustrative, and in no sense restrictive, disclose the manner in which 25 the methods of the invention may be practiced and several types of containers which may be made in accordance with the methods. Apparatus is also disclosed which may be employed in practicing the methods, but it will be understood that different apparatus may be designed to carry out the methods.

Figure 1 shows a blank of material such as one of metal from which the container closure is fabricated.

35 Figure 2 shows the blank after the same has been subjected to an initial step in the method, the blank still being in substantially flat condition.

Figure 3 is an enlarged view of one side of the 40 blank of Figure 2, after the sealing material has been applied thereto.

Figure 4 is a vertical sectional view through one type of apparatus and shows the manner in which a closure may be formed from the substantially flat blank of Figure 3.

45 Figure 5 is a partial vertical sectional view through the closure, showing a subsequent step which places the closure in condition for application to the container.

50 Figure 6 is a vertical sectional view through a conventional container such as a metal can, showing the closure applied thereto.

Figure 7 is a partial enlarged view similar to Figure 6, showing an apparatus in position to 55 seal the closure with the container.

Figure 8 is a partial vertical sectional view of the container and closure, showing the condition of the same after the sealing operation of Figure 7 has been performed.

60 Figure 9 is a view similar to Figure 7, showing another manner in which the closure may be sealed with the container.

Figures 10, 11 and 12 show modified forms of the container and closure which may be made 65 in accordance with the method of the present invention.

Referring to Figure 1, 10 designates a flat blank 70 of appropriate material such as metal, from which the closure is to be fabricated. This blank may be of any desired configuration, but will usually be circular to conform with a cylindrical container. This blank is formed into the condition shown in Figure 2, in which figure the blank has a groove 12 depressed in the portion 11 thereof which is to form the vertical

area or skirt of the closure. The groove 12 forms a closed path surrounding the center of the blank. The groove may be depressed in any desired manner, as by a stamping operation, and will be circular and concentric with the blank 5 when the closure is to be applied to a cylindrical container. It will be noted that the back 13 of the groove or depression 12 extends below the lower wall of the blank forming a protuberance, so that the metal of the groove may be 10 operated upon in a manner hereinafter described.

Figure 2 also shows the formation of a cup-shaped portion 14 in the blank which is to form the closure. This operation may be conveniently performed at this stage of the method in order 15 that the resulting closure will permit the containers to be stacked without becoming stuck to one another. However, the operation is not an important part of the method, and may be dispensed with if desired, and the blank of Fig- 20 ure 2 will be hereinafter referred to as being in "substantially flat" condition in spite of the illustration of the cup-shaped portion 14 in the blank.

The "substantially flat" condition may include 25 any condition of the blank in which the groove 12 is in such position that the liquid sealing material may be applied thereto in an even manner and will not flow from the groove as would be the case were it attempted to apply the sealing material after the vertical area 11 of the blank is bent therefrom into a skirt portion.

After the groove 12 has been formed in the blank, and while said blank is in the substantially flat condition of Figure 2, a plastic sealing material 15 is disposed in the groove. This sealing material will preferably be flowed into the groove 12 in liquid condition, and will be permitted to solidify therein before the performance of the succeeding operation of the method. 40 If the sealing material is applied to the groove 12 in liquid condition, it will completely and evenly fill said groove and upon solidification will be adhesively bound with the inner walls of the groove. While the sealing material is shown 45 applied to the groove so that its upper surface is flush with the upper face of the blank 10, an additional amount of said material may be applied within the groove so that the material will protrude beyond the upper surface of the 50 blank in order to provide a tighter seal when the closure is applied to the container.

While it is preferred that the sealing material be applied to the groove 12 in liquid condition, it is possible that a solid or semi-plastic ring 55 of the sealing material may be disposed in the groove 12 after which heat may be applied so that said material will assume substantially the configuration of the groove, and adhere thereto.

After the sealing material has solidified in 60 the groove, the vertical area or skirt portion 11 of the blank is bent therefrom in the manner shown in Figure 4. In this figure, a suitable die apparatus is disclosed, comprising a lower female die 20 having an annular channel 21 therein, and an upper male die 22 having an annular male die member 24 for cooperation with the channel 21. The upper die may be provided with a plate 25 adapted to rest upon the annular abutment 65 26 of the lower die member to retain the blank at point 28 where the vertical area 11 is bent from the blank. The plate 25 may be equipped with a circular projection 30 for cooperation with a circular depression 31 in the lower die 20 in 70 75 75

order to fit the cup-shaped portion 14 of the blank.

In performing the bending operation, the substantially flat blank of Figure 2 will be positioned 5 on the lower die 20 with the portion 28 thereof disposed above the annular projection 26 on the lower die, to properly locate the bend in the metal of the blank. The blank may be aligned on the lower die member in any convenient manner, and 10 a convenient means for accomplishing the alignment may be provided by the seating of the cup-shaped portion 14 of the blank within the circular depression 31 in the lower die.

When the blank is thus positioned in the lower 15 die, the area 11 thereof extends outwardly and horizontally over the opening of the annular channel 21 in the lower die, and when the upper die is lowered, the annular male die member 24 thereof will engage the upper surface of the area 20 11 of the blank, and bend the same downwardly through substantially 90° to form the vertical skirt of the closure. The bend is made along a line between the center of the blank and the groove 25 12. During this operation, the male die member 24 will move downwardly into the annular channel 21 forcing the area 11 of the blank into said channel. The lower die may be equipped 30 with any suitable cushioning means to assist in the bending operation, and as shown in Figure 35 4, an annular follower 35 is positioned in the channel 21, said follower being mounted on a bolt 36 which is urged upwardly in channel 21 by a spring 37.

It will be observed that the diametrical dimension 35 of the channel 21 is slightly greater than the diametrical dimension of the male die member 24, by a distance equal to the thickness of the metal of the blank 10 plus the depth of the depression 12 in said blank. Furthermore, it 40 will be noted that the outer wall of the die member 24 is in contact with the outer wall of the channel 21 during the bending operation so that a space 39 is left between the inner wall of the male die member 24 and the inner wall of the 45 channel 21, this space being sufficient so that the groove 12 of the blank will not be distorted and the sealing material 15 will not be disturbed in its position in said groove during the bending operation.

50 After the vertical skirt 11 has been formed on the blank, an inwardly directed bead 40 may be rolled on the end of said skirt, as shown in Figure 5, this being done in any approved manner. The bead is rolled in such fashion that a flat area 41 is formed at the outer termination of the skirt, which area is adapted to engage the end of the container in a manner which will hereinafter be apparent.

The closure preformed as discussed above, is 60 applied to the container in the manner illustrated in Figure 6 preliminary to the sealing of said closure with the wall of the container. A container of conventional type in the form of a metal can 42 having a longitudinal side seam 43 is shown, and it is evident that difficulty would be 65 encountered in tightly sealing the open end of such a container with a conventional closure, due to the disfiguration of the inner contour of the mouth of the container caused by the fold of the side seam 43.

In order to tightly seal such a container, the closure has been equipped with the groove 12 filled with the sealing material 15 in the manner described above.

75 It will be noted that the metal can 42 has a

full pouring opening, the flow of the contents therefrom being unimpeded by any devices such as conventional seamless neck rings which when applied, generally extend inwardly a material distance from the wall of the container toward the 5 axis thereof. Furthermore, no pockets near the container mouth are formed when a container of the type illustrated is used, and no paint can be trapped with consequent wastage.

The closure is inserted into the container 10 mouth until the bead 40 of the closure engages the outwardly rolled bead 45 on the mouth of the container. When inserted, the open or front side of the annular groove 12 will face the inner wall 15 of the container and the sealing material 15 in 20 the groove will be in contact with the inner wall of the container. The exterior diameter of the skirt portion 11 of the closure will preferably be of the same diameter or slightly greater than the internal diameter of the mouth of the container, 25 so that the closure will fit tightly therein. The outer surface of the sealing material may be even with the outer surface of the skirt portion 11 of the closure, or it may protrude slightly beyond the surface of said skirt portion in order to more 30 intimately engage the inner wall of the container.

While a closure applied in the manner shown in Figure 6 will be reasonably effective in sealing a 35 container, it is desirable to form a seal which 30 will absolutely preclude the possibility of leakage from the container during transportation by the loosening of the closure, such additional insurance against leakage being necessary in the packaging of paints and the like, which are of 35 high specific gravity.

In Figure 7 a device is illustrated which is useful in sealing the closure in the container mouth, as for transportation purposes. This device comprises a plunger 47 of such configuration that it 40 may move downwardly into the annular recess 48 in the outer wall of the closure, said plunger being of such dimension and being so positioned that it will engage the back surface 43 of the channel 12 as at 49, and will upset the metal of 45 the back wall of the channel and force the same toward the wall of the container, resulting in the compression of the sealing material 15 within the channel against the wall of the container. The plunger 47 has connected therewith a plate 51 50 which overlies the side wall of the container 42 and a follower 53 is connected with and below plate 51 for limited relative movement with respect to the same by means of a bolt 54, there being a spring 55 mounted on said bolt between 55 plate 51 and follower 53. By this construction, the follower 53 yieldingly engages the upper edge of the bead 40 of the closure and maintains the same in engagement with the bead 45 of the container. When the plunger 47 is moved toward 60 the applied closure to seal the same, the follower 53 will first engage the upper edge of the bead 40, and force the bead into engagement with the upper edge of the head 45, and during subsequent action of the plunger, the follower will yieldingly 65 maintain the plug closure in position.

In Figure 8, the condition of the skirt 11 and groove 12 is disclosed after said groove has been upset by forcing its back wall inwardly toward the wall of the container and it will be observed 70 that the rear wall of the groove is flattened out but that the adjacent walls of the skirt 11 have not been distorted. It will be apparent that the sealing material will be firmly compressed against the wall of the container, so that there is no 75

possibility of accidental removal of the closure.

When it is desired to use the contents of the container, the plug may be initially removed by inserting a coin or other tool between the bead 40 of the closure and bead 45 of the container to pry the closure loose. The sealing material having been initially permitted to solidify in the groove 12 will not be pulled therefrom during the removal of the closure due to its adhesive engagement with the inner wall of the groove.

When the closure is removed, a complete pouring opening from the container will be provided.

After the contents of the container have been partially used, and it is desired to reapply the closure, the same may again be forced into position in the container, and the sealing material 15 will again form an effective sealing contact with the wall of the container.

A closure provided simply with a ring gasket of rubber in the annular groove in the skirt of the closure will not form as effective a seal as the sealing material disclosed herein, which is initially applied to the blank of metal before the same is formed into a closure, and which material is forced firmly into sealing engagement with the container wall after the preformed closure is applied. An ordinary loose gasket in the sealing groove would be rolled from the groove and distorted during the insertion of the plug into the container, and if not seriously damaged during the insertion of the plug, it would undoubtedly be injured during the removal of the plug, particularly if the gasket had been pressed into intimate engagement with the container wall in the manner disclosed above.

The disposition of the sealing material within the groove 12 protects the material from direct contact with the contents of the container because the groove is spaced from the inner end of the plug by the annular projecting portion 59 of said plug. When the plug is reinserted after once having been removed, the portion 59 of the plug will scrape away any paint or the like along the wall of the container so that the sealing material 45 will engage substantially bare metal.

It is preferred to initially seal the plug with the container wall in the manner described above. A similar result may be obtained, if, after the plug is inserted, the wall of the container is spun inwardly toward the open face of the groove 12 in the manner shown in Figure 9. While any convenient type of tool may be utilized to perform this operation, I have shown a roll 60 which is moved into engagement with the wall of the container in alignment with the groove 12, and pressure is applied against the wall of the container to annularly indent the same as at 61. The indented portion of the container serves to compress the sealing material 15 within the groove 12 so that accidental removal of the plug will be precluded. In this arrangement, the sealing material will preferably extend out beyond the engaging wall of the skirt 11, so that it will not be necessary to force the metal of the indentation 61 of the container into the groove 12. That is, only sufficient indentation of the container wall to engage the protruding sealing material is necessary, so that the closure may be removed after initial application without interference between the indentation 61 and the lower annular projecting portion 59 of the skirt of the closure.

Extreme pressure in indenting the wall of the container will not be necessary in connection with the present embodiment, owing to the fact that the groove 12 in the skirt of the closure is pre-

formed before application of the closure to the container, so that tool 60 need only indent the side wall sufficiently to compress the protruding packing 15, rather than indenting the skirt portion 11 of the closure as well as the wall of the container, as would be the case were the groove 13 not preformed in the skirt. If desired, any type of backing chuck may be disposed in the annular channel 48 of the upper face of the plug during the indenting operation.

In Figure 10 another type of closure and container is disclosed which may be manufactured practicing the method of the present invention.

The mouth of the container 42 in this modification is provided with an inwardly turned bead 65, and the closure has an inwardly curved resilient skirt portion 66 terminating at its inner or lower edge in an outwardly turned bead 67. Disposed in the annular depression on the outer wall of the skirt 66 above the bead 67 is a quantity of sealing material 68. The exterior diameter of the bead 67 of the closure is slightly greater than the internal diameter of the bead 65 of the container, and the skirt portion of the closure is of sufficient resiliency so that when the closure is forced into the open mouth of the container, the bead 67 of the closure will spring past the bead 65 on the container wall, permitting bead 65 to firmly engage the sealing material 68 when the skirt expands. When the closure is snapped into place, the bead 67 will lock beneath the bead 65.

The upper end of the skirt portion of the closure of the present embodiment is bent outwardly through substantially right angles and then back upon itself where it joins the upper face 70 of the closure, forming an annular projection 71. The closure of this embodiment may be removed as hereinbefore described by inserting a coin or the like between the upper face of the bead 65 and the lower face of the annular projection 71.

The sealing material 68 may be disposed in liquid condition on the closure of this embodiment while the same is in blank form and in substantially flat condition, in a manner similar to that shown in connection with the embodiment of Figure 3. The blank may be in substantially flat condition, with an annular depression formed by the curved skirt portion 66 therein, and sealing material is applied in this depression in substantially the same manner as shown in Figure 3. The sealing material will then be permitted to solidify, after which the skirt portion of the closure may be bent from the blank as hereinbefore disclosed.

The outer diameter of the projection 71 is substantially the same as the outer diameter of the container in the present embodiment, this arrangement permitting conservation of space when the containers are transported stacked side by side.

In Figure 11 another container and closure is disclosed which may be manufactured by practicing the method of the present invention. In this embodiment the mouth of the container 42 is provided with an inwardly pressed annular groove 75 in the wall of the container, said groove being spaced a short distance below said bead. The closure is equipped with an inwardly turned bead 76 adapted to overlie the bead 74 in a manner and for a purpose hereinbefore described, and the skirt portion of the closure is provided with an inwardly pressed annular recess 77 spaced from the inner wall 78 of the closure providing an annular shoulder 79 on the skirt below the recess 77. A sealing material 80 is

applied to the outer wall of the skirt above the recess 77, and in the corner where the skirt merges into the bead 76.

When this closure is forced into position in the container, the annular shoulder 79 on the closure will spring over the annular indentation 75 in the wall of the container so that the inner side of said indentation will enter the annular recess 77 in the skirt portion of the closure. Similarly to previous embodiments, the external diameter of the shoulder 79 is slightly greater than the internal diameter of the depression 75. The length of the skirt between the annular recess 77 and the lower face of the bead 76 of the closure is such that when the same is forced into position as shown in Figure 11, the gasket material 80 will be compressed between the wall 81 of the skirt and the inner face of bead 74 of the container, and between the lower face of the bead 76 of the closure and the bead 74 of the container.

Obviously the sealing material 80 may be applied to the closure blank of this embodiment when the same is in substantially flat condition, and before the skirt of the closure is formed from the blank, in a manner similar to the method disclosed in connection with the embodiment of Figure 3. The sealing material is applied in liquid form to that portion of the closure which forms the wall above the recess 77, when the closure is in blank form and in substantially flat condition, after which the vertical skirt portion of the closure will be formed from the blank as described in connection with the embodiment of Figure 3.

In the embodiment of Figure 12, the container is provided at its mouth with an inwardly turned bead 85 identical with the bead 65 of Figure 10, and the closure has a resilient skirt portion 86 of slightly greater diameter than the internal diameter of the bead 85. The upper end of the skirt portion 86 terminates in an internal annular channel 87 which merges at 88 into an inwardly rolled bead 89 which is adapted to overlie the container bead 85. The sealing material 90 is disposed within the channel 87 in the outer wall of the skirt portion of the closure, and when the closure is inserted, the skirt portion 86 will engage the bead 85 and will be compressed as said skirt portion moves by said bead, and the skirt portion will spring beneath the lower edge of the bead 85 so that the latter will enter the annular channel 87 and compress the material 90 therein to secure a firm engagement of the closure with the container. In this embodiment, the closure 53 may be removed by inserting a coin or the like between the beads 85 and 89 in a well-known manner.

It will also be noted that the external diameter of the bead 89 of the closure is substantially equal to the external diameter of the container so that containers of this character may be stacked adjacent to one another with their side walls in contact with one another. Furthermore, the sealing material 90 of this embodiment may be applied to the blank from which the closure is formed while said blank is in substantially flat condition and before the skirt portion is bent from the blank, in a manner similar to the method described in connection with the embodiment of Figure 3. The sealing material is applied to this closure in liquid condition when the same is substantially flat, said material being flowed into the smaller channel 87 and permitted to solidify therein, after which the vertical skirt portion of the blank is formed.

Various modifications of the devices, methods and apparatus disclosed in this application may be made without departing from the scope of the invention.

I claim:

1. The method of manufacturing and applying to containers, a closure of the type having a vertical skirt adapted to engage in sealing contact with the wall of the container, which comprises providing a substantially flat closure blank, forming a depression in the blank in a portion thereof which is to form the skirt, said depression forming a closed path surrounding the center of the blank, disposing a plastic sealing material in said depression while the blank is in substantially flat and unformed condition, causing the material to solidify in said depression and adhere to the blank, bending the vertical skirt from the blank on a closed line between the center of the blank and said depression with said depression and sealing material in said area, applying the formed blank to the mouth of the container with the skirt in engagement with the wall of the container and the open side of said depression facing the container wall, and sealing the container by indenting the wall thereof opposite said depression toward the open side of said depression to force the sealing material therein into intimate engagement with the container wall.

2. The method of manufacturing a container closure of the type having a vertical area adapted to engage in sealing contact with the container, which comprises providing a closure blank having a substantially flat peripheral area, forming a cup-shaped portion in the blank symmetrically disposed with respect to its center and within said peripheral area, and a depression in one face of said peripheral area spaced from and surrounding the outer edge of said cup-shaped portion, and thereby forming a corresponding protuberance on the other face of said peripheral area, disposing a plastic sealing material in said depression while said peripheral area is substantially flat and said blank in unformed condition, causing the material to solidify in said depression and adhere to the blank, and then bending said peripheral area from the blank with said depression and solidified sealing material therein to form the vertical area of the closure before applying the closure to the container.

3. The method of manufacturing a container closure of the type having a cylindrical vertical area adapted to engage in sealing contact with the container, which comprises providing a circular closure blank having a substantially flat peripheral area, forming a cup-shaped portion in the center of the blank and a concentric annular depression in one face of said peripheral area spaced from the outer edge of said cup-shaped portion, and thereby forming a corresponding protuberance on the other face of said peripheral area, disposing a plastic sealing material in said depression while said peripheral area is substantially flat and said blank in unformed condition, causing said material to solidify in said depression and adhere to the blank, and then bending said peripheral area from the blank with said depression and sealing material therein to form the cylindrical vertical area of the closure, before applying the closure to the container.

4. The method of manufacturing a container closure of the plug type having a vertical area adapted to engage in sealing contact with the inner wall of the container, which comprises providing a closure blank having a substantially flat

- peripheral area, forming a cup-shaped portion in the blank symmetrically disposed with respect to its center and within said peripheral area and a depression in one face of said peripheral area spaced from and surrounding the outer edge of said cup-shaped portion, and thereby forming a corresponding protuberance on the other face of said peripheral area, disposing a plastic sealing material in said depression while said peripheral area is substantially flat and said closure in unformed condition, causing the material to solidify in said depression and adhere to the blank, and then bending said peripheral area from the blank to form the vertical area of the closure with said depression and the solidified sealing material therein on the outer wall of the vertical area, before applying the closure to the container.
5. The method of manufacturing a container closure of the type having a vertical area adapted to engage in sealing contact with the container, which comprises providing a substantially flat closure blank, forming a depression in one face of the blank in a portion thereof which is to form the vertical area and thereby forming a corresponding protuberance on the other face of the blank, said depression forming a closed path surrounding the center of the blank, disposing a plastic sealing material in said depression while the blank is in substantially flat and unformed condition, causing the material to solidify in said depression and adhere to the blank, and then bending the vertical area from the blank on a closed line between the center of the blank and said depression, with said depression and solidified sealing material in said area, before applying the closure to the container.
6. The method of manufacturing a container closure of the type having a cylindrical vertical area adapted to engage in sealing contact with the container, which comprises providing a circular substantially flat closure blank, forming an annular depression in one face of said blank symmetrically disposed with respect to the center thereof in a portion of the blank which is to form the vertical area, and thereby forming a corresponding protuberance on the other face of the blank, said depression forming a closed path surrounding the center of the blank, disposing a plastic sealing material in said depression while the blank is in substantially flat and unformed condition, causing said material to solidify in said depression and adhere to the blank, and then bending the cylindrical vertical area from the blank on a closed line between the center of the blank and said depression, with the depression and solidified sealing material in said area, before applying the closure to the container.
7. The method of manufacturing a container closure of the plug type having a vertical area adapted to engage in sealing contact with the inner wall of the container, which comprises providing a substantially flat closure blank, forming a depression in one face of the blank in a portion thereof which is to form the vertical area, and thereby forming a corresponding protuberance on the other face of the blank, said depression forming a closed path surrounding the center of the blank, disposing a plastic sealing material in said depression while the blank is in substantially flat and unformed condition, causing the material to solidify in said depression and adhere to the blank, bending the cylindrical vertical skirt from the blank on a closed line between the center of the blank and said depression, with said depression and the solidified seal-

ing material on the outer wall of the vertical area, before applying the closure to the container.

8. The method of manufacturing a container closure of the plug type having a cylindrical vertical area adapted to engage in sealing contact with the inner cylindrical wall of the container, which comprises providing a circular substantially flat closure blank, forming an annular depression in one face of the blank in a portion thereof which is to form the vertical area, and thereby forming a corresponding protuberance on the other face of the blank, said depression forming a closed path surrounding the center of the blank, disposing a plastic sealing material in said depression while the blank is in substantially flat and unformed condition, causing the material to solidify in said depression and adhere to the blank, and then bending the vertical area from the blank on a closed line between the center of the blank and said depression, with the depression and solidified sealing material on the outer wall of the vertical area, before applying the closure to the container.

9. The method of manufacturing and applying to containers a closure of the type having a vertical skirt adapted to engage in sealing contact with the wall of the container, which comprises providing a substantially flat closure blank, forming a depression in one face of said blank in a portion thereof which is to form the skirt and thereby forming a corresponding protuberance on the other face of the blank, said depression forming a closed path surrounding the center of the blank, disposing a plastic sealing material in said depression while said blank is in substantially flat and unformed condition, causing the material to solidify in said depression and adhere to the blank, forming the vertical skirt from the blank with the depression and solidified sealing material therein, applying the formed blank to the mouth of the container with the skirt in engagement with the wall of the container and the open side of said depression facing the container wall, and sealing the container by upsetting the metal of the skirt forming said protuberance to force the sealing material into intimate engagement with the container wall.

10. The method of manufacturing and applying to containers a closure of the type having a cylindrical vertical skirt adapted to engage in sealing contact with the cylindrical wall of the container, which comprises providing a circular substantially flat closure blank, forming an annular depression in one face of the blank symmetrically disposed with respect to the center thereof, in a portion of the blank which is to form the skirt, and thereby forming a corresponding protuberance on the other face of the blank, said depression forming a closed path surrounding the center of the blank, disposing a plastic sealing material in said depression while the blank is in substantially flat and unformed condition, causing the material to solidify in said depression and adhere to the blank, bending the cylindrical vertical skirt from the blank on a closed line between the center of the blank and said depression, with said depression and the sealing material in said skirt, applying the formed blank to the mouth of the container with the cylindrical skirt in engagement with the cylindrical wall of the container and the open side of said depression facing the container wall, and sealing the container by upsetting the metal of the skirt forming said protuberance to force

the sealing material into intimate engagement with the container wall.

11. The method of manufacturing and applying to containers a plug closure of the type having a vertical skirt adapted to engage in sealing contact with the inner wall of the container, which comprises providing a substantially flat closure blank, forming a depression in one face of said blank in a portion thereof which is to 5 form the skirt, and thereby forming a corresponding protuberance on the other face of the blank, said depression forming a closed path surrounding the center of the blank, disposing a plastic sealing material in said depression 10 while the blank is in substantially flat and unformed condition, causing said material to solidify in said depression and adhere to the blank, bending the vertical skirt from the blank on a closed line between the center of the blank and 15 said depression, with said depression and the sealing material in said skirt, applying the formed blank to the mouth of the container with the skirt in engagement with the inner wall of the container and the open side of said depression 20 facing the container wall, and sealing the container by upsetting the metal of the skirt forming said protuberance to force the sealing material outwardly into intimate engagement with the container wall.

12. The method of manufacturing and applying to containers a plug closure of the type having a cylindrical vertical skirt adapted to engage in sealing contact with the inner cylindrical wall of the container, which comprises providing a circular substantially flat closure blank, forming 5 an annular depression in one face of the blank concentrically disposed with respect to the center thereof, in a portion of the blank which is to form the cylindrical skirt, and thereby forming a corresponding protuberance on the other face 10 of the blank, said depression forming a closed path surrounding the center of the blank, disposing a plastic sealing material in said depression while the blank is in substantially flat and unformed condition, causing the material to 15 solidify in said depression and adhere to the blank, bending the cylindrical vertical skirt from the blank on a closed line between the center of the blank and said depression, with said depression and the sealing material on the outer 20 wall of the skirt, applying the formed blank to the mouth of the container with the skirt in engagement with the inner wall of the container and with the open side of said depression facing the container wall, and sealing the container by 25 upsetting the metal of the skirt forming said protuberance to force the sealing material outwardly into intimate engagement with the container wall.

HARRY SEEBELL. 30
